COMBINATION CAP AND SCREW DRIVER FOR CONTAINER OF LIGHTER FLUID

Charles A. Byrne, Washington, D. C.

Application January 4, 1956, Serial No. 39,597

Term of patent 14 years

(Cl. D58—26)

FIG. 1

FIG. 2

FIG. 3

FIG. 4

Fig. 1 is a front elevational view of a combination cap and screw driver for container of lighter fluid showing my new design;

Fig. 2 is an elevational view thereof taken from the right side of Fig. 1;

Fig. 3 is a bottom plan view thereof; and

Fig. 4 is a top plan view thereof.

I claim:

The ornamental design for a combination cap and screw driver for container of lighter fluid, as shown.
